MISCELLA REFINING

Robert O. Schmitt, Cincinnati, Ohio, assignor to The Buckeye Cellulose Corporation, Cincinnati, Ohio, a corporation of Ohio

Application October 11, 1957, Serial No. 689,713

5 Claims. (Cl. 260—426)

This invention relates to the refining of solvent extracted vegetable oils and more particularly to the refining of such oils in the presence of the extraction solvent.

Refining processes involving the addition of an aqueous alkaline refining agent to a solvent solution of extracted oil are well known to the art and are characterized by the phase "miscella refining." When contacted with the alkali, the fatty acids present are converted into soap; mucilaginous material such as phosphatides, proteins and gums are precipitated; and coloring matter and other undesirable impurities are removed from the oil, along with any soap which has been formed. The precipitate thus formed is commonly referred to in the art as "foots." The oil solvent serves to minimize the loss of neutral oil by emulsification with the foots.

In the refining of oil-solvent solutions (hereinafter referred to as miscellas) removal of color to meet edible standards is difficult but may be effected by continued agitation of the miscella with the refining lye over a long period of time or by agitation with large excesses of the refining lye. However, either of these expedients is conducive to excessive oil saponification and an attendant increase in oil loss.

The point in miscella refining at which the process of color removal has proceeded to substantial completion is designated by those skilled in the art as the "color break." This color break is determined as follows. Upon admixture of lye with the miscella, the foots which are formed initially contain only minor amounts of color. If a small amount of this mixture of miscella and foots is placed on a piece of filter paper, the foots appear as colored, immobile masses; and the dark colored miscella is absorbed by the filter paper and spreads to form a dark colored circle. After further agitation and during the latter stages of miscella refining, however, the foots particles form dispersed aggregates containing most of the colored constituents originally present in the oil. The point of "color break" is that point at which removal of color has proceeded to the extent that when a portion of the mixture of foots and miscella is placed on filter paper, the foots particles appear as dark colored immobile masses, and clear refined miscella is absorbed by the filter paper and spreads to form a substantially colorless circle.

The primary object in miscella refining is to obtain a thorough dispersion of the refining lye in the miscella so that maximum contact between the lye and color bodies in the oil occurs, thereby enabling an earlier color break and more complete color removal. When the suspended foots coalesce and agglomerate to form large foots aggregates at a point early in the refining operation, a substantial amount of the refining lye is entrapped within the aggregates; and the quantity of available refining lye is insufficient to effect satisfactory color reduction. In such a case it is often necessary to subject the recovered oil to a second refining in order that its color may be sufficiently light to meet current standards for edible use, as in shortenings for example. Moreover, when the color break is delayed, valuable time is lost, costs of operation are increased, and neutral oil recovery is diminished through increased saponification of the oil.

Since saponification of neutral oil is minimized under

2

conditions which promote an early color break, refining procedures which lessen the time necessary to achieve this color break are highly desirable. One such procedure has been described in Folzenlogen U. S. Patent 2,563,327, wherein the desired results are achieved by agitation of the refining lye and miscella in the presence of certain non-ionic ethers. These ethers, however, constitute an expense item of some importance, and a process enabling substantial reduction in the required amount of the ethers, accompanied by an earlier color break and reduced operating costs, would constitute a genuine advance in the art.

It is an object of the present invention to provide an improved process for refining solvent extracted vegetable oils in the presence of the extraction solvent, whereby color removal from the oil is effected in a greatly reduced time, at reduced cost, and with a minimum of saponification of neutral oil.

It is a further object to provide an improvement on the processes described and claimed in U. S. Patent 2,563,327.

In one of its aspects, this invention is based on the discovery that seeding crude miscella with a portion of the foots which have been separated from miscella in a previous refining, such seeding to be conducted prior to the addition of the refining lye and in the presence of a minor amount of any of the non-ionic ethers described and claimed in U. S. Patent 2,563,327, unexpectedly through a synergistic action promotes a color break in a much shorter time than has heretofore been possible through the use of such ethers alone. In the complete absence of the above mentioned non-ionic ethers, the seeding of crude miscella with a portion of the foots which have been separated from miscella in a previous refining will reduce the color break time substantially. It has been observed that such seeding of crude miscella with recirculated foots and particularly with non-ionic ethers present results in the formation of foots which in the presence of conventional agitation remain uniformly dispersed in the miscella throughout the entire color removal operation, thereby promoting an early color break and substantially complete color removal.

As will be noted from the following detailed description, the essential distinguishing features of the refining procedure of this invention over those procedures heretofore employed in the art resides in the recirculation of a portion of the foots from a previous refining and particularly in the presence of much smaller quantities of the non-ionic ethers of U. S. Patent 2,563,327 than have heretofore been required, resulting in a consistently early color break.

The invention will be better understood by reference to the drawings, wherein:

Figure 1 is a flow chart of a preferred method of practicing the invention wherein non-ionic ethers are employed, and

Figure 2 is a graph which shows the effect of recirculating foots, with and without non-ionic ether, on color break time.

Referring to the drawings, Figure 1 depicts a typical commercial batch miscella refining operation in which crude cottonseed oil in hexane solution is refined with sodium hydroxide in large vented closed kettles 10. The kettles have a capacity of about 500 cubic feet, are cylindrical in shape and have a domed top and a conical bottom. Each kettle is provided with an internal steam coil for heating the charge and an agitator for mixing.

In a conventional refining operation, aqueous refining lye from storage 12 is introduced into a charge of crude miscella in such a refining kettle, and the agitators are set to revolve at about 70 revolutions per minute or at

such speed as may be required to effect adequate dispersion of the lye. It will be understood, of course, that the degree of agitation is not a critical limitation and will, in fact, vary depending upon kettle construction and the type, size and shape of the agitator. The agitation is continued until the undesirable color has been removed from the oil, i. e. until a color break is noted, at which time the mixture of refined miscella and suspended foots is dropped to a drop tank 13 equipped with adequate agitation to keep the foots in uniform suspension, prior to passage to a centrifugal separator. From this drop tank the mixture passes through a pump 14 to a closed centrifuge 15 which separates the refined miscella from the foots. The refined miscella goes to a surge tank 16 and is then separated into solvent and neutral oil fractions by conventional methods. The foots mixture is collected in a surge tank 17 and heated by passage through a heat exchanger 18. The solvent is then separated from the foots-water-solvent mixture in a flash evaporator 19 and condenser 20. The foots are subsequently processed in a conventional manner, and the solvent is returned to the system.

In the practice of the invention the crude miscella is seeded by returning a portion of the foots discharged from evaporator 19 through pipe 21 by metering pump 22 to kettle 10, and non-ionic ethers are introduced from tank 11, the seeding being accompanied by sufficient agitation to effect a uniform dispersal of the foots and ethers throughout the miscella prior to the addition of the aqueous refining lye. The foots which are employed for seeding may also come from the surge tank 17, and the heat exchanger 18 and the lines connecting these points.

The miscella coming from the extraction step usually contains more solvent than oil, but the refining procedure of this invention does not require large quantities of solvent and it may be desirable from the standpoint of economy in handling, storage, etc., to remove a portion of the solvent before performing the refining operation. Such reductions in the amount of solvent can be achieved by the usual evaporation facilities known in the art. It is preferred that the refining procedure be carried out on miscellas containing from about 25 percent to about 60 percent oil.

In practices involving refining substantially immediately after extraction or miscella concentration, the temperature of the miscella may be well above 100° F., as it is charged to the refining equipment. If necessary the temperature of the miscella can be adjusted before the addition of the recirculated foots, non-ionic ethers if employed and refining lye. In the practice of the present invention, ordinarily the refining is conducted at temperatures of from about 100° F., to 140° F. Temperatures substantially above 140° F., generally tend to induce the formation of large foots aggregates rather than the desirable fine foots dispersion, thereby causing a delayed color break and incomplete color removal. The rate of reaction between the refining lye and the color bodies in the oil is slowed appreciably at temperatures substantially below 100° F. Preferably the refining is conducted at temperatures from 115° F., to 125° F., when the miscella is constituted of about 40 to 60 percent oil in commercial hexane.

The advantages of this invention are also realized when the miscella is constituted of volatile oil-extraction solvents other than hexane. Thus improved results in color reduction are also noted in the case of miscellas formed by the use of extraction solvents such as benzene, heptane, commercial mixtures containing such hydrocarbons, and other volatile aliphatic and aromatic hydrocarbon oil extraction solvents and solvent mixtures known in the art. The invention is of particular advantage, of course, in the refining of those miscellas formed in the use of solvents which dissolve a considerable quantity of high colored constituents from the oil-bearing meats.

It has been found that aqueous solutions containing

from about 5% to about 20% sodium hydroxide may be used, final choice depending on the refiner's judgment, arrived at after consideration of the nature of the miscella being refined.

5 The amount of aqueous alkali used in the miscella refining techniques of this invention will normally be 100-175 percent of the maximum percent sodium hydroxide prescribed by the rules of the National Cottonseed Products Association in the regular refining of hydraulic cottonseed oils of the same free fatty acid content figured as oleic acid (percent NaOH=percent F. F. A./5.2+.54). Under normal conditions and with normal hexane miscellas, obtained in the extraction of cottonseed oil for example, 125-150 percent of maximum 10 will suffice. However, amounts below 125%, such as 15 50%, and amounts in excess of 150%, such as 225%, can be employed, depending on the nature and amount of impurities in the oil of the miscella being refined.

The recirculated foots which are added to the refining 20 kettle in the practice of this invention can be removed from the refining system at any point, although for convenience the foots are preferably obtained just after the evaporation of the solvent. It will be apparent, of course, that there may be mechanical means for pumping the 25 foots directly to the refining kettle from the removal point in the system or that the foots can be manually transported to the refining kettle from such point.

Amounts as small as about 10 pounds of foots (containing about 70% by weight of water and about 30% 30 by weight of non-volatile material comprising soap; neutral oil; mucilaginous material such as phosphatides, proteins and gums; coloring matter and alkali) are sufficient, with and without the added presence of non-ionic ether, to substantially reduce the color break time of miscellas 35 containing 50% hexane and 6000 pounds of oil. Thirty to fifty pounds of foots are normally employed in the manner and with the results set forth in the preceding sentence and amounts of foots substantially in excess of 50 pounds per 6000 pounds of oil in the form of a 50% 40 miscella have resulted in a substantially reduced color break time.

As stated hereinbefore, any of the non-ionic ethers described in Folzenlogen, U. S. Patent 2,563,327, can be employed in the practice of this invention. These non-ionic ether compounds are liquid at about 80° F., and are of the group consisting of (1) ethers of polyhydric alcohols, said alcohols containing from two to three hydroxyl groups and having from two to eight carbon atoms in the carbon skeleton, and (2) non-ionic derivatives of 45 such of said ethers as contain unreacted hydroxyl groups. Of these non-ionic ethers set forth in the Folzenlogen patent, polypropylene glycol having a molecular weight of about 400 is preferred for use in the present invention. An amount as small as about 0.05 pound of non-ionic 50 ether is sufficient in combination with recirculated foots to substantially reduce the color break time of miscellas containing 6000 pounds of oil. The use of greater quantities of the non-ionic ethers is, of course, permissible, and no adverse effects have been observed when such 55 greater quantities have been employed. However, the use of non-ionic ethers in quantities substantially greater than the 0.05 pound set forth above only increase the cost of the refining operation to an extent which is disproportionate to the benefit gained from the increased usage.

Example I

The following table exemplifies the results obtained in a series of several batch refinings of cottonseed oil hexane 70 miscella at 115° F., and the data reported therein designate clearly the beneficial effect of seeding with foots from a previous refining, both with and without the presence of non-ionic ethers. The particular non-ionic ether employed is a polypropylene glycol having an 75 average molecular weight of 400 (hereinafter designated

P-400), and hexane is the solvent. Fooths containing 70% by weight of water and 30% by weight of non-volatile material comprising soap; neutral oil; mucilaginous material such as phosphatides, proteins, gums; coloring matter, and alkali) from a flash evaporator are added to the refining kettle along with a charge of 1600 gallons of the designated crude miscella and the P-400 when used. Continuous agitation is used during the filling cycle and for the designated periods of time after completion of the filling cycle. After this premixing period, water and a 20% sodium hydroxide solution are added simultaneously in the amounts designated in the following table. The titration values in the table below represent the milliliters of 0.25 N. sodium hydroxide required to neutralize the acidic material in 50 ml. of the crude miscella. In these refinings, as in all refinings within the scope of this invention, a premixing time of about two minutes prior to the addition of the lye is required to completely disperse the fooths, P-400 when used and any accompanying water in the crude cottonseed miscella. With adequate premixing the crude miscella darkens considerably, indicating the presence of a very fine dispersion. After the lye is added there is produced a very fine grain fooths which settles very slowly in the absence of agitation and contributes to good centrifuge operation. If there is insufficient premixing, the color break time will increase and large fooths particles will be produced, resulting in excessive neutral oil losses in the fooths. The premixing may extend for an indefinite period of time without adverse effect on refining.

Batch No.	Gallons H ₂ O	Percent Oil in Miscella	Titration	Gallons 20% NaOH	Lbs. P-400	Lbs. Fooths	Premix, Minutes	Break Time
A	9.2	50.6	3.1	33.0	0	0		40
B	9.2	50.6	3.1	33.0	0	5	4	8
C	9.2	50.6	3.1	33.0	0	50	4	6

H	9.2	50.6	3.1	33.0	0.05	60	4	3
I	9.2	50.6	3.1	33.0	0.05	60	30	4
J	9.2	50.6	3.1	33.0	0.1	5	4	7
K	9.2	50.6	3.1	33.0	0.1	60	4	4

Prior to the discovery of the advantageous action of recirculating fooths from a previous refining and non-ionic ethers in reducing break time, it was necessary to continue agitation of the miscella-lye mixture for an average time of about 20 minutes, with even longer times often being required. The use of the non-ionic ethers described in U. S. Patent 2,563,327 was an unquestioned advance in the art and lowered the break time to an average of about 15 minutes, although variation still presented some problems. Seeding the crude miscella with fooths from a previous refining and non-ionic ethers has reduced the normal break time to from 2 to 8 minutes, and the consistency of break time which has been achieved allows a much smoother refining operation. Furthermore, the recirculation of fooths has not only resulted in a consistently low break time but, has reduced non-ionic ether usage from 200-500 ml. per 1600 gallon batch of miscella containing 6000 pounds of oil to as little as 25 ml. per batch.

Substantially identical results are observed when soybean oil is substituted for the cottonseed oil employed in this example.

Example II

The graphical representation set forth in Figure 2 is the result of a series of separate refinings, and it shows clearly the reductions in color break time which can be achieved by recirculating varying quantities of fooths, both in the presence and absence of non-ionic ether. Experimental conditions include 1600 gallons of a cottonseed oil hexane miscella at 100° F., containing 40% by

weight of oil, 10 pounds of fooths from a previous refining, 0.1 pound of dipropylene glycol when used, a premixing time of 3 minutes, an amount of sodium hydroxide sufficient to provide 125% of the maximum prescribed by the National Cottonseed Products Association and a titration value (as explained hereinbefore) of 3.1.

The above description of the invention has been confined specifically to miscellas obtained in the extraction of cottonseed oil and soybean oil, and the invention is of particular importance in the case of cottonseed oil miscellas. However the advantage of greatly reduced color break time, at reduced cost, and with a minimum of saponification of neutral oil, is realized in the refining of miscellas obtained in the solvent extraction of other oleaginous materials.

However, although the specific description of the invention has been related to batch refining, it is to be understood that the advantages of the invention may also be realized by recirculating separated fooths in the presence of non-ionic ethers in continuous refining procedures employing continuous mixing of miscella and alkali refining agent followed by continuous centrifugal separation of the refined miscella and precipitated fooths.

Having thus described my invention, what I claim is:

1. In the process of refining vegetable oils in solution in volatile solvents, the steps which comprise seeding such solution with fooths which have been separated from miscella in a previous refining, premixing the combination of solution and recirculated fooths to obtain a uniform dispersion prior to the addition of alkali refining
